UNITED STATES PATENT OFFICE.

PAUL E. SCHLEICHER, OF CHICAGO, ILLINOIS, ASSIGNOR TO SCHLEICHER, INC., OF GARY, INDIANA, A CORPORATION OF ILLINOIS.

KNOCKDOWN RADIATOR COVER.

Application filed June 28, 1924. Serial No. 722,974.

This invention relates to a radiator hood which may be readily assembled and disassembled, the parts of which are so constructed that they are susceptible of being 5 kept in stock and readily used to form different sizes of covers; and in which a novel supporting structure for the water pan is provided.

The invention comprises the novel structure and combinations hereinafter described and more particularly pointed out and defined in the appended claims.

In the accompanying drawings which illustrate a preferred embodiment of this invention and in which similar reference numerals refer to similar features in the different views:

Figure 1 is a side elevational view of the radiator hood.

20 Figure 2 is an end elevational view of the same.

Figure 3 is an enlarged sectional view upon the line 3—3 of Figure 1.

25 Figure 4 is an enlarged fragmentary sectional view through the upper part of the hood showing my novel supporting means for the water pan.

Referring to the drawing, it will be noted that I have illustrated a radiator cover or 30 hood having a perforated section in the front and ends, the back being a solid sheet of metal. The hood however may be of any other design since the invention relates more particularly to a structure for supporting the water pan in a hood so that 35 the same may be readily removed.

The frame is constructed of four corner posts 1 which are in the form of pressed metal angle members, a solid plate 2 is 40 bolted or secured to the two rear posts to form the back of the hood. An upper strip of metal 3 is secured between the two front posts. This upper strip 3 has an interior depending support 3^a which is formed by re-bending a portion of the strip upon itself and forming a flange upon its depending end. A lower strip 4 is also secured between the front posts 3 and a perforated section or metal sheet is attached to the adjacent 45 margins of the strips 3 and 4 and the front posts 1.

Transverse strips 9 and 10 are secured between the front and back posts as shown in

Figure 2. These strips may be secured to the posts in any suitable way.

55 Suitable foraminous sheets are secured in the end panels of the cover and a frontal foraminous sheet 11 is secured between the strips 3 and 4 and the posts 1. These foraminous sheets are preferably secured in 60 position by means of strips 12 secured to the posts and strips 12 secured to the posts and frame as shown in Figure 3. These strips may be secured to the border parts of the screened openings in any suitable 65 way.

An adjustable supporting foot or shoe 16 of similar contour to the posts 1, fits upon the lower end thereof, for vertical adjustment with respect thereto. A screw 70 17 projects from the bottom of each shoe and extends through a support 18 welded or secured in any appropriate manner to the interior of each post. This screw is provided with a pair of nuts 19 and 20 lying 75 upon opposite sides of the support 18 for confining the shoe or foot in an adjusted position.

A water pan 21 is supported in the upper 80 end of this hood, one longitudinal margin of said pan resting upon the support 3^a. The opposite side of the pan may be suspended from the back 2 of the hood by means of suitable brackets 22 (only one of 85 which is shown) which are in the form of a U-shaped member having upper rebent portions or hook-like ends which respectively engage over the back 2 of the hood and the upper margin of the pan 21; a suitable supporting strip 23 is pivotally attached 90 to the lower end of the U-shaped bracket 22 for supporting the humidifier. This supporting strip 23 may be swung on its pivot for removal of the humidifier. A cover 24 is adapted to fit over the frame for closing the 95 upper end thereof.

It will be appreciated that the water pan is securely held in position in spaced relation to the rear wall of the cover to provide a passage for air currents, and that the 100 pan may be readily removed by swinging the bracket 23 to disengage the pan from the hook shaped end of the supporting bracket 22.

I am aware that numerous details of construction may be varied through a wide 105

range without departing from the principles of this invention, and therefore do not purpose limiting the patent granted otherwise than necessitated by the appended claims.

5 I claim as my invention:

1. In a radiator hood comprising a frame having a rear metal wall and a front strip having a supporting flange, U-shaped brackets supported from the back, a swingable support upon each bracket, and a water pan supported on said flange and said supports, said brackets spacing the water pan from the back to allow for air currents.

10 2. In a radiator hood comprising a frame having a support on one side, a U-shaped bracket suspended from the other side, a swingable support upon said bracket, a water pan supported upon said supports,

one end of said bracket engaged over said pan, and said bracket spacing the pan from the side of the cover to provide a passage for air currents.

15 3. In a radiator hood comprising a frame having a support upon one side, U-shaped brackets suspended from the other side, a swingable support pivoted to the base of each bracket, a water pan resting upon said supports and spaced from one side of said frame by said brackets to provide a passage for air currents, said supporting brackets having upper hook shaped ends respectively engaging over the upper edges of said water pan and the wall of said cover.

20 In testimony whereof I have hereunto subscribed my name.

PAUL E. SCHLEICHER.
